which is heated to a high temperature. The fuel is introduced into the heating chamber 21 and is ignited. The heat from the burning fuel is conducted through the walls of the chamber 21 to the water contained in the heating chamber 16. The water is heated and passes through the nozzle 13 and into the blades 14 of the rotor 9. The steam is then exhausted through the exhaust opening 11.

UNITED STATES PATENT OFFICE

2,002,497

HIGH VAPOR EXPANSION TURBINE

Homer M. Barber, Reno, Nev.

Application February 3, 1933, Serial No. 655,123

1 Claim. (Cl. 122—41)

This invention relates to improvements in power apparatus and has particular reference to a device for creating and using superheated steam.

The principal object of this invention is to produce a device wherein the losses incident to ordinary reciprocating steam engines will be materially reduced.

A further object is to produce a power plant which is exceedingly compact and efficient in operation.

A further object is to produce a power plant wherein various load requirements may be handled without the employment of the customary gear changing which is found in many types of transmissions.

A still further object is to produce a device which is economical to manufacture.

Other objects and advantages will be apparent during the course of the following description.

In the accompanying drawings forming a part of this specification and in which like numerals are employed to designate like parts throughout the same,

Fig. 1 is a side elevation of my engine as the same would appear in use.

Fig. 2 is a cross sectional view on the line 2—2 of Fig. 1.

Fig. 3 is a plan view of the top plate with the burners removed.

Fig. 4 is a fragmentary cross sectional view showing the steam nozzle.

Fig. 5 is a bottom view of the cap, and showing the heating chambers welded thereto, and

Fig. 6 is a fragmentary view of the rotor showing several of the blades in cross section.

It is my purpose in creating this engine to employ a super-heated steam which is derived by injecting a small quantity of water against an extremely hot surface, whereby this water is instantaneously turned into steam, which steam is further superheated and expanded under high pressure. This expanded steam then issues directly through a nozzle against the blades of a rotor, which rotor is keyed to a shaft from which shaft power may be derived. The exhausted steam may be condensed if desired and returned to a small capacity tank from which it would be pumped back into the generating chamber to again be recirculated through the system.

In the accompanying drawings wherein for the purpose of illustration is shown a preferred embodiment of my invention, the numeral 5 designates a shaft mounted in bearings 6 which are carried upon a support 7. Side plates 8 spaced

form a housing for a rotor 9. These plates have exhaust openings 11, the purpose of which is obvious. Mounted upon the plates 8 and supported thereby, is a generator 12 having a nozzle 13 formed therethrough, which nozzle is adapted to direct a jet of steam against the blades 14 of the rotor 9. This generator 12 has an expansion chamber 16. In order to close this chamber I provide a cap 17 which is held to the generator by bolts 18. A flange 19 serves to effect a seal between the cap and generator.

Welded to the generator is a plurality of heating chambers 21. Each of these heating chambers is provided with a burner inlet 22, the purpose of which will be later seen. Water feed pipes are shown at 23 and it will be noted that these said pipes terminate in restricted openings 24 so that a very fine stream of water will be projected against the rounded surface of balls 20. The generator and cap is preferably enclosed in a protective covering 26 of heat insulating material such as volcanic ash, and a shell 27.

The operation of my device is as follows:—

Assuming that the device is constructed as shown in Figs. 1 and 2, we will assume that the fuel pipes in Fig. 1 conduct fuel to burners preferably employing butane gas, which burners, when ignited, discharge their products of combustion into the chambers 21. These chambers are heated to a high heat after which water is forced through the pipes 23 and jets 24 against the balls 20, and as a result this water contacting the surface of the balls forms a mist which will be expanded by the heat of the heating chambers and will become super-heated steam. This steam now under high pressure will seek to escape and as the only means of escape is through the nozzle 13, the same will be directed against the blades 14 of the rotor 9. It is obvious that with this high pressure of steam impinging upon the rotor, the same will be revolved thus delivering power to the shaft 5. If desired the steam which will be exhausted from the rotor may be condensed, returned to a small tank and will then be re-conveyed by a pump, through the system in which case while on its second cycle, the water in the tank will have been raised in temperature to a considerable degree and as a result the generating process will be much accelerated.

I have found from experiments conducted, that this engine will operate under a pressure of 2000 pounds to the square inch and deliver a speed of vapor at the periphery of the wheel at 5000 feet per second. With this type of engine I have eliminated the customary boiler and

small tubes which are liable to burst under such heavy pressure, and am only employing heavy castings which may be easily designed to withstand high pressures and excessive heat for long periods of time without deterioration.

It will thus be seen that I have produced a device which will accomplish all the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:—
In a high pressure generator, a heating chamber, a plurality of heating elements extending into said heating chamber, said elements being spaced one from the other, the outer surfaces of said heating elements being in close proximity to the surface of said heating chamber, each of said heating elements having a recess formed therein, the recesses of the adjacent heating elements being opposed to each other, a ball positioned between said heating elements and within said recesses, means for injecting fine jets of water against said balls, and an outlet port communicating with said heating chamber.

HOMER M. BARBER. 15
